UNITED STATES PATENT OFFICE

WILLIAM O. MICHELS, OF WOODHAVEN, NEW YORK, ASSIGNOR TO ROYAL TYPEWRITER COMPANY, INC., OF NEW YORK, N. Y., A CORPORATION OF NEW YORK

TYPEWRITING MACHINE

Application filed October 22, 1927. Serial No. 227,997.

This invention relates to a type action for typewriting machines in which there are a plurality of sliding type bars which converge to a common printing center and each type bar is provided with a plurality of groups of two type each. Each type bar is operated by two key levers for the purpose of selecting the desired type of each group and the platen is shifted in the usual or any desired manner in order to bring it into a position to cooperate with the selected group of types.

The sliding type bars are actuated by a toggle mechanism which reaches a straight line position at the time of printing so that the actual printing is performed by pressure rather than by impact. Means are provided for obtaining a relative adjustment between the normal position of the platen and the type bars in order that the force of the imprint may be varied as may be desired for manifolding.

One of each pair of keys merely gives the type bar its sliding movement, while the other key not only gives the type bar the same sliding movement, but gives a slight lifting movement to a guide member which supports the type bar in its travel to the printing point, thereby lifting the bar into position so that another type of the group is brought to the printing point. The type bar is given its sliding and lifting movements at substantially the same time but the lifting movement is completed before the type bar reaches the printing point and the connections between the second key lever and the guide which lifts the type bar are such that the key lever may be moved a slight further distance after the guide has reached the full extent of its movement.

The invention also comprises power operated mechanism for actuating the type bars by which either or both of the above-described movements are given to the operated type bar.

Further details of the invention will be apparent from the following description and set forth in the appended claims.

In the drawings:

Figure 1 is a side elevation of a single type

action with parts in fore and aft section with the parts in normal position.

Figure 2 is a similar view showing the parts in operated position when the type bar is actuated to print from the lowermost type 55 of a group.

Figures 3 and 4 are side elevations of a portion of the power driven mechanism showing different stages in the operation thereof.

Figure 5 is a side elevation of a modification.

Figure 6 is a top plan view of a portion of the structure shown in Figure 5.

The invention may be embodied in typewriting machines of widely different character in other respects, and for this reason the other instrumentalities of the typewriting machine have not been illustrated. There is indicated a platen A which is movable to a second position indicated in dotted lines by 65 70 any usual or desired form of case shift mechanism.

Each type bar 1 is mounted to slide and is preferably made in skeleton form for the sake of lightness and is provided with four 75 types a, b, c, and d. When the platen is in its lower position as shown in Figure 1, operation of the type bar will print from one of the type c or d. If the type bar is given merely its longitudinal movement, the printing 80 impress will be from the type c as indicated in Figure 1 while if the type bar is simultaneously lifted by the depression of the other key which operates the same, the imprint will be from the type d as shown in Figure 2. If it is desired to print from types a or b, the platen is shifted to the dotted line 85 position and the two key levers control the selections of the types a or b in similar manner.

Each type bar 1 slides on a supporting and guiding member 2 which is pivoted at 3 to a fixed part of the machine and has upstanding ears 4 which bear against one side of a type bar and guide it in its movement. 95 Riveted or otherwise fastened to the member 2 at 5 is a plate 6 which extends upwardly and has bent over ears engaging the upper edge of the type bar. The projections 4, plate 6, and ears 7 engage the type bar at 100

different points along its length and serve to guide the same accurately to the printing point.

Attached to an intermediate portion of the type bar at 8 is a link 9 which is illustrated as being formed with two parallel members connected by web portions 10. This is primarily for convenience in manufacture and to add stability to the parts and is preferable since 10 one of the guide members passes on each side of the type bar and serves to guide the rear end thereof in its movement. It is possible, however, to omit the web portions 10 and employ two separate parallel links, or a single 15 link member may be used.

Pivoted at 11 to the link 10 is a short link 12 which, together with the link 10, forms a toggle member. This link 12 is pivoted at its other end to a supporting member 14 mounted in the frame of the machine. An extension 15 from the member 14 passes through a bar 16 carried by the machine frame and a screw 17 threaded into the bar 16 has a head 18 engaging the cut-out 19 in the member 15 so that the position of the member 15 may be adjusted by turning the screw 17. A set screw 20 may be employed to lock the member 15 in adjusted position. It is obvious that an adjustment of this member 20 will adjust the position of the link 12 which forms one member of the toggle and will, therefore, vary the effective printing position of the type bar.

Pivoted at 21 to an ear on the link 12 is a link 22 which is pivoted at its other end at 23 to a lever including a pair of arms 24, one arm of which passes on each side of the member 15. This lever is pivoted to the member 14 at 25 and one of the arms is extended 40 downwardly as indicated at 26. A spring 27 connected at one end to the member 14 and at its other end to an ear 28 carried by the member 26 tends to hold the parts thus far described in the Figure 1 position.

The lower end of the extension 26 is pivoted at 29 to a link 30 having an arm connected by a spring 31 to an ear on the extension 26. The lower end of the link 30 is pivoted at 32 to a rock arm or member 35 loosely mounted on a shaft 33 which is kept in constant rotation by any suitable source of power. A ratchet wheel 34 is fast on said shaft and rotates therewith. A detent member is pivoted at 36 to the rock arm or member 35 and has a tooth 39 adapted to be brought into engagement with the ratchet wheel 34. A forked arm 37 loosely mounted on the shaft 33 and adjustable in its position, has a guard 38 which overlies the ratchet wheel for a purpose hereinafter set forth.

Key levers 40 and 41 are pivoted on a suitable axis and are adapted to connect the action proper to the power driving mechanism in the following manner. The key lever 40 is connected by a link 42 to a lever 43 pivoted

on an axis 46 and having a bent over ear 44 which overlies an arm 45 also pivoted on the axis 46. The key lever 41 is connected by a link 50 with a short lever 51 pivoted on the axis 46 and lying on the other side of the lever 45 and has an ear 52 overlying the same. The arm 45 has an extension 48 to which is connected one end of a spring 47, the other end of which is connected to a member 49 carried by the frame which tends to hold the lever 45 in the Figure 1 position. The lever 51 has an upward projection 53 for a purpose hereinafter set forth and the lever 45 has a broadened end 54 adapted when the parts are in normal position to lie in front of an ear 55 on the upper end of the rock arm or member 35 and also to overlie a portion 56 of the detent or pawl member pivoted at 36.

The arm 53 is connected by a link 57 to a latch member 58 having a slot 59 adapted to engage a pin 60 carried by the ear 28 on the lever extension 26. This latch member is connected by a lost motion pin and slot connection 61 with the rear end of the lifting and guiding member 2. A spring 62 connected to the latch 58 and to the member 2 tends to retain the parts in the Figure 1 position.

A spring 63 connected at one end to the member 2 and at its other end to a frame member 49 tends to hold the member 2 in the Figure 1 position in which a stop member 65 contacts with the frame member 64. When the member 2 is shifted to bring the lower type of each group to the printing position as is shown in Figure 2, a stop 66 carried by the member 2 engages the under side of a portion of the frame member 64 to limit the lifting movement of the type bar.

The operation of the construction thus far described may be briefly set forth as follows. If the parts are in the Figure 1 position, and the key lever 40 is depressed, this will through the link 42 pull down on the lever 45, the end of which is in engagement with the portion 56 of the detent member carried by the member 35 and will swing this detent member until the tooth 39 thereof engages the constantly rotating ratchet wheel 34. The position of the parts at this moment is substantially that shown in Figure 3. The rotation of the ratchet wheel 34 with the shaft 33 will now move the detent and the arm 35 which carries the same to the Figure 4 position, thus swinging the link 30 and moving the whole train of connections to the type bar to move the same towards printing position. Just after the detent passes the Figure 4 position, it comes in contact with the guard 38 and is thrown out of engagement with the ratchet wheel to the Figure 2 position, which position it reaches just as the printing takes place. The spring 31 will thereupon return the type action and all connected parts substantially to the Figure 1 position regardless of whether the pressure on the key lever is released or

not. If the key lever is held down, the arm 45 will be held in depressed position and the 5 detent member will contact with the arm as shown in the dotted line position of Figure 2. The broad end 54 of the arm 45 will prevent this detent member from moving above the arm 45 and as soon as the key lever is allowed to return to its normal position, the parts will then reach the Figure 1 position, the ear 55 of the member 35 contacting with the broad end 54 of the lever 45 and preventing overthrow of the parts.

If the key lever 41 is depressed, the action above described will take place. In addition thereto, the lever 41 will produce a movement of the arm 53 and link 57 and will move the latch 58 into engagement with the pin 60 so that the rocking movement of the lever extension 26 will move this latch downwardly 20 to the Figure 2 position and consequently raise the type end of the type bar to the position shown in that figure to bring about printing from the lowermost type *d*. It will be noted that the ears 44 and 52 each overlie 25 the arm 45 so that this arm can be operated from either key lever without interfering with the other.

The member 37 which carries the guard 38 can be adjusted in its normal position by 30 means of a slot 67 in said member engaging a pin 69 carried by a rotatable part 68 but eccentric thereof. As shown in Figure 4, the rotation of the member 68 will vary the normal position of the part 37 and guard 38 35 and, therefore, vary the point at which the detent will be thrown out of engagement with the ratchet wheel 34.

In the modified form shown in Figures 5 and 6, the lever 43 is omitted and the link 42 is connected directly to the arm 45, which is provided with a returning spring 70. The key lever 41 is connected by the link 50 to the lever 51 exactly as in the first form, but in this case the lever 51 is provided with a separate returning spring 71. The key lever 40 45 is also provided with an individual returning spring 72. Carried by an ear 73 on the lever 51 is an eccentric 74 which overlies the arm 45 and the position of which may be adjusted by rotating. Suitable lock nuts are provided for holding this in adjusted position.

In this modification a depression of the key lever 40 will move the lever 45 directly and 55 will tension the two springs 70 and 72. A depression of the key lever 41 will move the lever 51 and through the overlying eccentric 74, the lever 45, thus tensioning the two springs 70 and 71. The key lever 41 of each 60 group needs no return spring of its own. In the case of both levers two returning springs are tensioned so that the touch may be made uniform.

The supporting and guiding member 2 is 65 normally inclined slightly below the horizon-

tal and when lifted to bring the type *d* into printing position, it moves to an equal distance above the horizontal. This results in the same action in both positions of the type bar. The provision of separate adjusting means for each type bar allows the printing position thereof to be varied individually. Any old and common means for adjusting the position of the platen relative to the type bars may also be employed if desired.

It is obvious that portions of the invention are applicable to the construction in which the key levers are actuated manually to transmit movement to the type action. It is also obvious that other forms of power actuating mechanism might be employed in connection with the specific type action illustrated. Various modifications may be made in the detail construction and the arrangement of parts and in general it is to be understood that the invention is to be regarded as limited only by the scope of the appended claims.

I claim as my invention:

1. A type action comprising a slidable type bar provided with a plurality of groups of type, key levers associated with the type bar and corresponding in number to the number of type in each group, a movable support for the type bar, power operated means controlled by the depression of each key lever for sliding the type bar to the printing position including a lever, a latch carried by the movable support, and means operated by the depression of one key lever for connecting the latch to the power operated lever.

2. A type action comprising a slidable type bar provided with a plurality of groups of type, key levers associated with the type bar and corresponding in number to the number of type in each group, a pivoted support for the type bar, power operated means controlled by the depression of each key lever for sliding the type bar to the printing position, means operated by the depression of one key lever for connecting the pivoted support to the power operated means, and means permitting the power operated means for sliding the type bar to operate after the pivoted support has reached the limit of its movement.

3. A type action comprising a slidable type bar provided with a plurality of groups of type, key levers associated with the type bar and corresponding in number to the number of type in each group, a pivoted support for the type bar, power operated means controlled by the depression of each key lever for sliding the type bar to the printing position, a latch carried by the pivoted support, means for moving said latch into operative engagement with the power operated means, and means for operating said moving means by the depression of one of the key levers.

4. A type action comprising a slidable type

bar provided with a plurality of groups of type, key levers associated with the type bar and corresponding in number to the number of type in each group, a pivoted support for the type bar, power operated means controlled by the depression of each key lever for sliding the type bar to the printing position, a latch loosely carried by the pivoted support, means for moving the latch into operative engagement with the power operated means, and means for operating said moving means by the depression of one of the key levers, the loose engagement of the latch permitting the means for sliding the type bar to operate after the pivoted support has reached the limit of its movement.

5. Power driving means for type bar actions comprising a constantly rotating shaft, a ratchet wheel thereon, an arm loosely mounted on said shaft, a detent pivoted on said arm, means for moving said detent into engagement with the ratchet wheel so that the arm will rotate with the shaft, means whereby the movement of the arm will actuate the type bar action, means including a plurality of key levers for independently operating the said detent moving means, means supporting the type bar for movement in another direction, and means operated by one of said key levers for connecting the supporting means to the power driving means.

6. Power driving means for type bar actions comprising a constantly rotating shaft, a ratchet wheel thereon, an arm loosely mounted on said shaft, a detent on said arm, key operated means for moving said detent into engagement with the ratchet so that the arm will rotate with the shaft, means whereby the movement of the arm will actuate the type bar action, a guard for the ratchet wheel loosely mounted on the shaft for cooperation with the detent to disengage the latter from the ratchet wheel, and means for circumferentially adjusting the guard about the shaft.

7. Power driving means for type bar actions comprising a constantly rotating shaft, a ratchet wheel thereon, an arm loosely mounted on said shaft, a detent on said arm, key operated means for moving said detent into engagement with the ratchet so that the arm will rotate with the shaft, means whereby the movement of the arm will actuate the type bar action, a guard for the ratchet wheel loosely mounted on the shaft for cooperation with the detent to disengage the latter from the ratchet wheel, said guard being provided with a slotted arm, and means including an adjustable eccentric engageable with the slotted arm of the guard to circumferentially adjust the latter about the shaft.

8. A type action comprising a slidable type bar provided with two groups of type, two key levers associated with the type bar, a vertically movable support for the type bar,

a power mechanism for the type action including a constantly rotating shaft, a member loosely mounted on the shaft, a detent pivotally mounted on the member for engagement with the ratchet wheel, connections between the member and the type bar for moving the latter along the support upon engagement of the detent with the ratchet wheel, an arm pivoted on a fixed axis for moving the detent into engagement with the ratchet wheel, a pair of levers independently engageable with the pivoted arm, separate connections between the levers and the key levers whereby upon depression of either key lever the arm will be moved to engage the detent with the ratchet wheel, and means connected with one of the pivoted levers for moving the type bar support vertically upon depression of one key lever only.

9. A type action comprising a slidable type bar provided with two groups of type, two key levers associated with the type bar, a vertically movable support for the type bar, a power mechanism for the type action including a constantly rotating shaft, a member loosely mounted on the shaft, a detent pivotally mounted on the member for engagement with the ratchet wheel, connections between the member and the type bar for moving the latter along the support upon engagement of the detent with the ratchet wheel, an arm pivoted on a fixed axis for moving the detent into engagement with the ratchet wheel, a pair of levers independently engageable with the pivoted arm and fulcrumed on the same axis, a spring for normally holding said pivoted arm out of engagement with the detent and in engagement with the levers, separate connections between the levers and the key levers whereby upon depression of either key lever the arm will be moved to engage the detent with the ratchet wheel, and means connected with one of the pivoted levers for moving the type bar support vertically upon depression of one key lever only.

10. Power driving means for type bar actions comprising a constantly rotating shaft, a ratchet wheel fixed thereon, an arm loosely mounted on said shaft, a detent pivoted on said arm and movable to either of two extreme positions, a stop to limit the movement of the detent in its inoperative position, a coil spring connected at its ends to the arm and to the detent respectively whereby the spring will function to yieldably retain the detent in either extreme position, said detent being normally held in its inoperative position by said spring, key operated means for moving said detent into engagement with the ratchet so that the arm will rotate with the shaft, and a stationary guard for the ratchet wheel which is engaged by the detent to throw the latter out of engagement with the wheel after a predetermined movement thereof.

11. A type action comprising a slidable

type bar provided with a plurality of groups of type, key levers associated with the type bar and corresponding in number to the number of type in each group, a movable support for the type bar, power operated means controlled by the depression of each key lever for sliding the type bar to the printing position, and means operated by the depression of one key lever for connecting the movable support to the power operated means to be operated thereby.

10 12. A type action comprising a slidable type bar provided with a plurality of groups of type, key levers associated with the type bar and corresponding in number to the number of type in each group, a movable support for the type bar, power operated means controlled by the depression of each key lever for sliding the type bar to the printing position including a lever, and means operated by the depression of one key lever for connecting the movable support to the power operated lever.

15 13. A type action comprising a slidable type bar provided with a plurality of groups of type, key levers associated with the type bar and corresponding in number to the number of type in each group, a pivoted support for the type bar, power operated means controlled by the depression of each key lever for sliding the type bar to the printing position, means operated by the depression of one key lever for connecting the pivoted support to the power operated means, and means for 20 limiting the pivotal movement of the support.

25 14. A type action comprising a type bar mounted for sliding and tilting movement, means for giving the type bar its sliding movement comprising a lever, power operating means, a plurality of keys for connecting said power operating means to said lever, means for giving the type bar its tilting movement, and means operated by one of said key levers for connecting this means to said lever.

30 40 45 In testimony whereof, I have hereunto subscribed my name.

WILLIAM O. MICHELS
